The ornamental design for a toy holder, as shown and described.

DESCRIPTION

FIG. 1 is an environmental perspective view of a toy holder showing my new design, with toys drawn in phantom lines; FIG. 2 is a top view thereof;

FIG. 3 is a bottom view thereof;

FIG. 4 is a front elevational view thereof;

FIG. 5 is a rear elevational view thereof; and,

FIG. 6 is a left side elevational view with the right side being a mirror image thereof.

The broken line showing of toys in FIG. 1 is for illustrative purposes only and forms no part of the claimed design.
